UNITED STATES PATENT OFFICE.

TRACY V. BUCKWALTER, OF ALTOONA, PENNSYLVANIA.

INTERNAL-COMBUSTION ENGINE.

1,245,188.

Specification of Letters Patent.

Patented Nov. 6, 1917.

Application filed May 18, 1914. Serial No. 839,423.

To all whom it may concern:

Be it known that I, TRACY V. BUCKWALTER, a citizen of the United States, residing at Altoona, in the county of Blair 5 and State of Pennsylvania, have invented certain Improvements Relating to Internal-Combustion Engines, of which the following is a specification.

My invention relates to internal combustion engines in which fuel is forced into a charge of highly compressed fluid in the combustion chamber where the fuel is ignited by the heated fluid and combustion effected. These engines, typified by the 15 utilization of highly compressed air for injecting liquid fuel into air heated by compression to a point above that required for igniting the fuel, are simplified in construction and operation and operated more 20 economically by means of my improvements, which contemplate the utilization of the heat in the waste gases discharged from the combustion chamber for evaporating water and utilizes the steam thus generated for 25 carrying the liquid fuel into the fluid compressed in the combustion chamber.

In the accompanying drawings, Figure 1 is a longitudinal sectional view of an internal combustion engine to which my improvements are applicable; Fig. 2 is an enlarged elevation of the engine having my improvements combined therewith; Fig. 3 is a part sectional elevation representing a second view of the construction shown in 35 Fig. 2; Fig. 4 is an enlarged sectional view taken on the line 4—4 of Fig. 3; Fig. 5 is an enlarged sectional view taken on the line 5—5 of Fig. 3; Fig. 6 is a sectional view of the atomizing disk taken on the line 6—6 of Fig. 5; Fig. 7 is a peripheral view of the 40 atomizing disk; and Fig. 8 is an enlarged sectional view taken on the line 8—8 of Fig. 5.

The mechanism illustrated in the accompanying drawings comprises the conventional engine cylinder 1 containing the piston 2 connected by the pitman 3 with the crank shaft 4; the cylinder being provided with the passage 5 having the port 6 through 45 which air is admitted back of the piston in the forward position thereof, the passage 7 having the port 8 through which air is forced into the cylinder in the backward movement of the piston, and the port 9 connected with a conduit 10 through which the 50 heated products of combustion are dis-

charged from the cylinder in the backward position of the piston.

In accordance with my invention, an eccentric 11 on the shaft 4 operates a pitman 12 to reciprocate a head 13 fixed to plungers 14 and 15 which act in the respective chambers 16 and 17 of a pump 18.

A conduit 19 delivers fluid fuel to the chamber 16 under control of a check valve 20 which controls the port 21, and a conduit 22 delivers the fluid fuel from the chamber through the inlet 23^a of the injector 23 which discharges into the top of the cylinder 1, the discharge from the latter conduit 20 back to the pump being prevented by a check valve 24 which controls the port 25.

A conduit 26, controlled by a check valve 27 normally seated on the port 28, delivers water to the chamber 17, which discharges 75 through the port 29, controlled by the check valve 30, to the conduit 31 connected with the inlet 23^b of the injector 23 back of the inlet 23^a. The inlet 23^b communicates with a circular channel 23^c which discharges 80 through the radial apertures 23^d to the injector chamber.

Coils 31^a of the conduit 31 are contained in a burned tube 32 through which flame is discharged from a nozzle or torch 33; and 85 coils 31^b of the conduit 31 are contained in the conduit 10 and heated by the waste products of combustion discharged from the engine cylinder 1.

The injector 23 contains an atomizing 90 ring or disk 34 provided with a peripheral channel 34^a in registration with the fuel inlet 23^a, the small radial passages 34^b which communicate with the channel 34^a, and the axial passage 34^c which communicates with 95 the passages 34^b.

A valve 35 controls the injector's aperture 23^c, by which it discharges into the cylinder 1, and passes freely through the aperture 34^c so that fluid will flow there-through, the shank of the valve passing through the packing 36 held in the rear of the injector. A nut 37 is engaged on the shank of the valve 35 and engages a coiled spring 38 supported by a yoke 39 fixed to 100 the injector, the spring acting through the nut on the valve to effect the closure of the aperture 23^c. A crank lever 40, fulcrumed on the bracket 41 is connected by the rod 42 with the head 13 and is adapted to act 105 upon the nut 37 in the upward movement of the head to withdraw the valve 35 from the 11.

port 23°, the valve being seated by the spring as the head descends.

In the operation of the engine, the oscillation of the pitmen 3 and 12 by the crank shaft 4, with resulting reciprocation of the piston 2 and plungers 14 and 15 are synchronized so that the plungers 14 and 15 are drawn back in the respective chambers 16 and 17, effecting the delivery of fuel oil and water to the respective chambers, as the piston 2 moves back in the cylinder 1; and as the piston moves forward in its cylinder, effecting the compression of air in front of it, the plungers force the oil and water through the respective conduits 22 and 31, the water being vaporized in passing through the coils 31^a heated by the burner 32 in starting and in passing through the coils 31^b heated by the waste gases flowing through the conduit 10 in the normal operation of the engine. The oil is delivered from the conduit 22 through the inlet 23^a of the injector into the channel 34^a of the disk 34 and thence through the passages 34^b and 34^c, by which it is disseminated. The steam is delivered from the conduit 31 through the inlet 23^b of the injector and thence through the channel 23^c and passages 23^d. As the cross head 13 approaches the upper limit of its stroke, the crank lever 40 is caused, by the action of the rod 42, to press against the nut 37 and draw back the valve 35 against the action of the spring 38, whereupon the highly compressed steam sweeps the oil through the aperture 23^e into the cylinder 1, where it is ignited by the heat of the air compressed in the cylinder and burns, as the piston moves backward in its working stroke.

The foregoing mode of operation and mechanism permits the elimination from slow combustion engines of apparatus for the compression of air to such high pressures as from 600 to 1000 pounds per square inch; saves the power required to drive such compressing apparatus; utilizes a portion of the energy of the exhaust gases in doing essential work in a simple manner; permits the use of small units heretofore impracticable because of the relatively high cost per unit of power, due chiefly to the necessity for air compressing apparatus; automatically provides an increase of the steam pressure for spraying fuel into the cylinder with in-

crease in load, due to the greater volume of hot gases available for the generation of steam under conditions of increased load; provides simple means adapted for starting multiple cylinder engines by the use of a portion of the heating coils in connection with an external supply of heat, as for instance a kerosene torch for the generation of steam for starting; secures the final delivery of the exhaust gases to the atmosphere at comparatively low temperatures due to the absorption of heat from such gases by the steam coils, and prevents, by the introduction of steam with the fuel, an extremely rapid combustion of the fuel with consequent high pressures, thereby reducing the explosive strains on the engine.

Having described my invention, I claim:

1. In an internal combustion engine, the combination with a cylinder and piston, of an injector communicating with said cylinder, a valve controlling communication between said injector and cylinder, conduits communicating with said injector, a pump having a plurality of chambers communicating with the respective conduits, plungers in said chambers, means for operating said plungers, and a device connected with said means for controlling said valve.

2. In an internal combustion engine, a cylinder and a piston therein, a conduit through which waste gases are discharged from said cylinder, an injector having a passage communicating with said cylinder, a pipe passing through said conduit to a connection with said injector, a second pipe connected with said injector, a valve for controlling said passage, a pump having chambers communicating with said pipes, check valves for preventing return flow from said pipes to said chambers, plungers operating in said chambers, means comprising a lever and a rod connected with said plungers for opening said valve first named, and means whereby said piston operates said plungers.

In testimony whereof I have hereunto set my name this 13th day of May, 1914, in the presence of the subscribing witnesses.

TRACY V. BUCKWALTER.
